206,915

DISPENSING CLOSURE OR SIMILAR ARTICLE

James M. Amburgey, Kendall Park, N.J., assignor to Colgate-Palmolive Company, New York, N.Y., a corporation of Delaware

Filed Dec. 13, 1965, Ser. No. 161

Term of patent 14 years

(Cl. D58—26)

FIG. 1

FIG. 2

FIG. 4

FIG. 1 is a perspective view of a dispensing closure or similar article showing my design with the slide in open position;

FIG. 2 is a top plan view with the slide in closed position;

FIG. 3 is an enlarged scale elevational view; and

FIG. 4 is a bottom plan view on the same scale as FIGS. 1 and 2.

The essential features of the design are shown in full lines on the drawing.

I claim:

The ornamental design for a dispensing closure or similar article, as shown and described.
